UNITED STATES PATENT OFFICE.

HENRY O. KELSEY, OF WEST SALAMANCA, NEW YORK.

SAW-TOOTH-DRESSING DEVICE.

SPECIFICATION forming part of Letters Patent No. 340,583, dated April 27, 1886.

Application filed February 10, 1886. Serial No. 191,481. (No model.)

To all whom it may concern:

Be it known that I, HENRY O. KELSEY, a citizen of the United States, residing at West Salamanca, in the county of Cattaraugus and State of New York, have invented a new and useful Improvement in Saw-Teeth-Dressing Devices, of which the following is a specification, reference being had to the accompanying drawings.

- 10 My invention relates to improvements in saw-teeth-dressing devices; and it consists, essentially, in a device adapted to receive one or more file-sections, to be set to receive saw-blades of different thicknesses, and, after having been set, to be operated by hand, for the purpose of dressing or sharpening saw-teeth, substantially as described hereinafter, and pointed out in the claims.

15 In the drawings, Figure 1 represents a perspective view of a saw-dressing device embodying my improvements. Fig. 2 represents a side view thereof. Fig. 3 is an edge view, and Fig. 4 is a sectional view on the line $x-x$ of Fig. 2.

20 Referring to the drawings, in which similar letters of reference denote similar parts, A designates a body or casting, preferably of brass, but which may be made of any suitable spring-metal. a designates a slit that extends from side to side of the casting and divides it into two parts, a' a'' . At the point a'' the slit is broadened and terminates at the lower end of the casting at a^4 in rounded portions a^5 , that operate as springs to open outward the parts a' a'' , as will be hereinafter set forth. The sides a' a'' are cut away at a^6 , for the purpose of forming side arms, b, that receive and hold file-sections B in recesses b^2 , formed in the adjacent inner faces of the side arms, b.

25 c c designate adjusting or gripping screws that extend from one to the other of the arms b at each side of the casting, as shown. The sides and bottom of the casting A are hollowed out or cut away, as shown at d d', for the purpose of lightening the casting.

30 D designates an adjusting-screw that passes

from one to the other of the sections a' a'' , for the purpose of adjusting said sections and their contained file-sections B nearer to or farther from each other to suit saws of different thicknesses.

35 In practice the sides a' a'' are adjusted to the proper distance from each other to permit a saw-blade to be introduced between the file-sections B. The casting is now moved back and forth, the file-sections B thereon operating to dress the sides of the teeth to a uniform thickness, as will be understood.

40 Modifications in detail of construction may be made in the herein-described invention without departing from the spirit or sacrificing the advantages thereof—as, for instance, blocks of emery may be used in lieu of the files.

I claim—

1. The improved saw-dressing device consisting of a casting, A, provided with a slit, a, to receive a saw, file-sections B, to dress the sides of said saw, and adjusting means to adjust said sections, substantially as described.

2. The improved saw-dressing device consisting of a casting having a slit, a, extending from its top nearly to its bottom, as shown, and arms b and transverse adjusting-screws c c, said arms having recesses b^2 , to receive file-sections B, and an adjusting-screw to adjust 75 said sections nearer to or farther from each other, substantially as described.

3. The body A, provided with a central slit or opening to receive the saw, and a file-section on each side of the opening, as set forth.

4. The body A, provided with a central slit or opening, forming arms, and seats a^6 in the arms to receive the file or emery sections, as set forth.

5. In testimony that I claim the foregoing as my own I have hereto affixed my signature in presence of two witnesses.

HENRY O. KELSEY.

Witnesses:

ALBERT A. BIRD,
JOSHUA E. CHAMPLIN.
